UNITED STATES PATENT OFFICE.

HENRY BROOKER, OF LONDON, ENGLAND.

COIN-FREED APPARATUS FOR DELIVERING PARTS FROM A STRIP.

Application filed April 8, 1918. Serial No. 227,369.

(GRANTED UNDER THE PROVISIONS OF THE ACT OF MARCH 3, 1921, 41 STAT. L., 1813.)

To all whom it may concern:

Be it known that I, HENRY BROOKER, a subject of the King of Great Britain, residing at London, England, have invented certain new and useful Improvements in Coin-Freed Apparatus for Delivering Parts from a Strip (for which I have filed an application in England April 4, 1917, No. 4,888, Patent No. 114,476), of which the following is a specification.

This invention relates to a coin-freed apparatus for delivering postage stamps, labels, admission tickets or the like from a strip, e. g., from a perforated strip, each part, unit or element of such strip, as existing between two sequent transverse rows of perforations, constituting a stamp, label, admission ticket or the like.

Apparatus according to the present invention is broadly of the class in which working force is introduced by the insertion of the coin.

The chief aim of the present invention is to render the operation of the apparatus certain, and to make the coin on ingress, do the mechanical work of setting or priming the apparatus, the setting device being a main rocking bar, preferably hinged at a level above the coin slot, while an easily actuated tripping mechanism released by the coin in its fall through or exit from the coin-track, serves to determine the delivery of the label or like with certainty and delicate sensitivity.

Further provision may be made for facilitating the entry of the coin by a supplementary push piece hinged to or bearing on the main rocking bar, so that the operator can by pressure thereon facilitate the entry of the coin.

There is provided a guillotine or equivalent to cut off each and every delivery so as to eliminate any possible pull or drag on the strip from the outside, also provision for such an association of parts as shall constitute an efficient machine which embodies the above features and other desirable characteristics. As a further aid to convenience and economy of effort on the part of the user a climb-up ratchet arrangement is embodied by which the setting for any stage in progress forward of the coin is preserved, and counts to the good. In other words to conserve effort, also to allow a return of the

setting device only after the final setting is arrived at, all stages in the application of energy are conserved by a step-by-step ratchet and pawl arrangement which however does not transmit drive when the mechanism operates for ejection after final setting but is then merely without hindrance to such operation. Thus the ratchet and pawl arrangement definitely prevents the mechanism from returning to the unset position until a certain predetermined setting is reached and thereafter allows the operation for ejection to take place; hence in this particular the invention is sharply distinguished from a climb-up ratchet which also forms an integral part of the drive when the mechanism operates for ejection and therefore cannot itself prevent the mechanism from returning to the unset position at any stage in the "winding-up" or setting of the machine.

The invention is described in detail by aid of the accompanying drawings.

Fig. 1 represents the chief parts of the mechanism as a face elevation of the mechanism as seen on the front of the main supporting plate, the facing side of the case being removed, while the coin slot or intake as also the strip discharge opening or put out are shown partly in section and partly in dotted line aspect.

Fig. 2 shows the back of the main supporting plate as a face elevation, the facing side of the case being removed, while the coin slot or intake and the coin discharge opening or put-out are indicated partly in section and partly in dotted line aspect. Other remote parts are also indicated by dotted outline.

Fig. 3 is a side view of the feeder, the feeder guide, and other adjacent parts.

The coin on its partial entry into the slot 1, Fig. 1, bears firmly against the lower edge 1^a of the slot and also against the push-piece 2, made adjustable firmly, as by screws 2^a, the arc on the periphery of the coin between 1^a and the push-piece 2 being, for example, about one third of the circle before the push-piece 2 begins to move.

The coin being now pressed firmly forward drives the push-piece 2 before it, and so causes the main rocking bar 3 to swing inwards on its centre at 3^a, this main rocking bar 3 operating the various parts requiring

power or setting and also being moved against the push of the leaf-spring 4.

As soon as the coin is forced so far into the slot that the grip between the lower 5 edge 1^a and the push-piece 2 embraces the full diameter of the coin, the machine is set or "wound-up," and the mechanism must be so adjusted that when the machine is fully "wound up" or set, the main rocking bar 10 3 engages by its lower extremity with the tripping release 5 which is given a bias towards the engagement position by a weighted head 5^a. The position of the lower end of the main rocking bar 3, when engaged with 15 the tripping release 5, is shown by dotted contour 3^b.

A further aid in the setting or "winding-up" of the machine is afforded by a special ratchet and pawl device, whereby setting 20 effort or "winding" is not wasted or let back: this being illustrated by Fig. 2 which shows in elevation the back of the main supporting plate. The main rocking bar 3 on the other side of the plate is here indicated 25 in dotted contour, and a pin 6 attached to the lower end of the bar 3, passes through an arc-like slot 3^c, in the plate. On the pin 6 is mounted a pawl 7, this pawl being capable of free or easy rotation on its pin, 30 with no bias other than that resulting from gravitation. Thus as the pawl trails upwards on the ratchet 8, it engages tooth by tooth, but as soon as the pawl 7 has passed the last tooth and hangs freely in the gap 8^a, 35 engagement of the main rocking bar 3 with a tripping release 5 takes place and the aid of the ratchet 8 is no longer required. As the pawl 7 now hangs in the hollow 8^a with its back towards the grip of the ratchet, the 40 main rocking bar can pass back to the unset position without hindrance, and as the pawl falls into the hollow 8^b it resets itself by gravitation for again functioning on the ratchet 8. Resetting may be assisted by a 45 weighted pendant 33 and a turning over of the pawl prevented by the guard pins 34, 34^a.

The coin falling through the coin track 9, breaks the engagement of the tripping release, with the main rocking bar 3, or 3^b, 50 as shown by Fig. 1, and the machine operates for ejection.

The operation of the guillotine for cutting off each unit or part at the appropriate line, for example, the line of perforations, 55 is illustrated by Fig. 1, 10 being the drop block which slides up and down on two pins, one of them being shown at 11, or one pin will serve, while 12 is the knife of the guillotine. The guillotine is lifted or set 60 by the rise of the arm 13, which itself is lifted by the adjustable tappet 40 on the bar 3 when the main rocking bar 3 is brought to the position 3^b, the catches 14 and 15 mutually engaging and keeping the guillotine up till the main rocking bar 3 returns to the 65

non-set position and through the agency of the adjustable tappet 16 acting on the rocker 17 releases the engagement of the catches 14 and 15.

In Fig. 1, 18 to 19 shows a sequence of 70 units on the perforated strip, the unit at 18 having been cut off by the guillotine and at the end 19 the strip terminates in a roll which is wound on the bobbin 20.

The feeder 21 is pivoted to bar 3 by a pin 75 21', and a lifting arm 22 is pivoted to the casing by a pin 22', and operates to raise the feeder 21 when the bar 3 is moved to its full extent forwardly. The arm 22 is operated by the fall of the guillotine block 10 so 80 that it raises a pin 23 which projects laterally from one side of the arm 22. When the bar 3 is moved rearwardly, the pin 23 is carried beyond the end of the arm 22, so that the front end portion of the feeder 85 descends by gravity, and the parts assume the positions shown in Fig. 3. The feeder is prevented from rising during its forward movement by means of a stationary guide 50 which projects over a pin 24 on the feeder 90 21, until the said pin passes forwardly beyond the front end of the guide, so that the feeder can be raised when the forward movement of the bar 3 is completed.

The coin track 9, 9, Fig. 1 includes a drop 95 out for under sized coins. Adjacent to and on the side of the aperture 25 of the main plate 26, the back of the track is cut out as at 41 so that it just fails to allow a coin of standard size and shape to drop through the 100 aperture 25, and to favour the falling out of under-sized coins, the track being sloped over a little towards the aperture 25 and further a light spring on the inner face of the outer wall of the track, shown in dotted 105 contour by 27, serves to aid in side tipping the under sized coin. The under sized coin thus side tipped through the aperture 25, is received by a chute 28, Fig. 2, which chute guides the coin to an exit slot for return. 110

In Fig. 1 at 30 is shown a counter linked to the main rocking bar 3 by the arms 31 and 32, and operating for count on the return of the main rocking bar to the unset position. 115

What I claim is:—

1. A coin freed automatic delivery machine for delivering units from a strip the said machine comprising, in combination, a main lever actuated and thus set to position 120 ready for effecting delivery of a unit by the action of inserting a coin in the machine, a detent or trip lever adapted to engage and hold the said main lever only when the latter has been moved to its fully set position and adapted to be disengaged from the main lever by the coin inserted, a strip feeder operable by the main lever for feeding the strip forward to the discharge opening or put-out of the machine, and means for hold- 125 130

ing the strip feeder clear of the strip during the setting movement of the main lever.

2. A coin freed automatic delivery machine for delivering units from a strip the said machine comprising in combination a main lever actuated and thus set to position ready for effecting delivery of a unit by the action of inserting a coin in the machine, a 5 detent or trip lever adapted to engage and hold the said main lever only when the latter has been moved to its fully set position and adapted to be disengaged from the main lever by the coin inserted, a strip feeder operable by the main lever for feeding the 10 strip forward to the delivery outlet of the machine, and a step-by-step ratchet and pawl device which retains partial movements of the main lever toward its fully set position and only allows the said lever to 15 return to its unset position and thus only allows operation of the strip feeder after the main lever has been moved to its fully set position.

3. A coin freed automatic delivery machine for delivering units from a strip the said machine comprising, in combination, a main lever actuated and thus set to position ready for effecting delivery of a unit by the action of inserting a coin in the machine, a 20 detent or trip lever adapted to engage and hold the said main lever only when the latter has been moved to its fully set position and adapted to be disengaged from the main lever by the coin inserted, a strip feeder operable by the main lever for feeding the 25 strip forward to the discharge opening or put-out of the machine, means for holding the strip feeder clear of the strip during the setting movement of the main lever, and a 30 push piece adjustably mounted on the main lever and against which the coin is pressed for moving the main lever to its set position.

4. In a coin freed apparatus of the kind referred to for delivering units from a strip, a 35 coin-receiving slot, a coin track, a setting device comprising a main rocking bar extending downwards to the lower part of the mechanism, said rocking bar being forced by the entry of a coin in the receiving slot 40 to move to setting position, a tripping device engaging the rocking bar at the end of the setting stroke, the tripping device being disengaged by the coin falling through the coin track, the rocking bar being adapted to 45 return automatically to its normal position, a device controlled by said rocking bar for cutting off a unit of the strip at the appropriate line, means on the rocking bar operating during the setting stroke for setting said 50 device, means on the rocking bar operating during the return stroke for releasing the device to perform its work, a strip feeder, and means operated by the cutting off device for raising the strip feeder into inoperative 55 position for retrogression from the

discharge opening or put-out, for the purposes described.

5. In a coin-freed apparatus of the kind referred to for delivering units from a strip, a coin-receiving slot, a coin track, a setting 70 device comprising a main rocking bar extending downwards to the lower part of the mechanism, said rocking bar for setting the apparatus being forced by the entry of a coin in the receiving slot to move to setting 75 position, a step by step ratchet and pawl device and a weighted pendant co-operating therewith and co-acting with the rocking bar in the setting of the apparatus, a tripping device engaging the rocking-bar at the 80 end of the setting stroke, the tripping device being disengaged by the coin falling through the coin track, means for returning the rocking bar to normal position, a device for cutting off a unit of the strip at the appropriate line, means on the rocking bar operating during the setting stroke for setting 85 said device, means on the rocking bar operating during the return stroke for releasing the device to perform its work, a 90 strip feeder and means operated by the cutting off device for raising the strip feeder into inoperative position for retrogression from the discharge opening or put-out, for the purposes described. 95

6. In a coin-freed apparatus of the kind referred to for delivering units from a strip, a coin-receiving slot, a coin track, a setting device comprising a main rocking bar hinged at a level above the coin-receiving slot, and extending downwards to the lower part of the mechanism, said rocking bar being moved rearwardly by the said coin, a weighted tripping device, engaging the rocking bar at the end of said movement, and being 100 disengaged therefrom by the coin falling through the coin-track, means for returning the rocking bar to normal position, a guillotine for cutting off a unit of the strip at the appropriate line, an adjustable tappet on 105 said rocking bar, and an arm in conjunction therewith, operating during the setting stroke to raise said guillotine, a catch on the guillotine, a rocker, a catch thereon engaging the first mentioned catch for setting the 110 guillotine, a second adjustable tappet on the rocking bar acting on the rocker during the return stroke to release the catches, from engagement, substantially as and for the purposes described. 115

7. In a coin-freed apparatus of the kind referred to and as claimed in claim 6, a strip feeder, an arm operated by the fall of the guillotine, a pin on the strip-feeder engaging said arm, substantially as and for the 120 purposes described. 125

In testimony whereof, I affix my signature.

HENRY BROOKER.
